US0D1100946S

(12) **United States Design Patent** (10) Patent No.: **US D1,100,946 S**
(45) Date of Patent: ** Nov. 4, 2025

(54) **DISPLAY SCREEN OR PORTION THEREOF
WITH A GRAPHICAL USER INTERFACE**

(71) Applicant: **IGT**, Las Vegas, NV (US)

(72) Inventors: **Ernest W. Moody**, Las Vegas, NV (US); **Yooehwan Hwang**, Las Vegas, NV (US); **Michael Fields**, Las Vegas, NV (US); **Christina Marie Foreman Harmon**, Sparks, NV (US)

(73) Assignee: **IGT**, Las Vegas, NV (US)

(**) Term: **15 Years**

(21) Appl. No.: **29/952,937**

(22) Filed: **Jul. 18, 2024**

Related U.S. Application Data

(62) Division of application No. 29/868,482, filed on Dec. 5, 2022, now Pat. No. Des. 1,042,503.

CLAIM

The ornamental design for a display screen or a portion thereof with a graphical user interface as shown and described herein.

DESCRIPTION

The FIGURE is a front view of a display screen or a portion thereof with a graphical user interface showing our new design.

The dashed broken line perimeter in the drawing illustrates a display screen or portion thereof and forms no part of the claimed design. The remaining dashed broken lines in the drawing illustrates portions of the graphical user interface that form no part of the claimed design.
